United States Patent Office

Des. 204,828
Patented May 17, 1966

204,828

COPY PAPER CARTON

Leo D. Sacre, Prospect Heights, Ill., assignor to American Photocopy Equipment Company, Evanston, Ill., a corporation of Illinois

Filed Feb. 23, 1965, Ser. No. 83,926

Term of patent 3½ years

(Cl. D58—12)

FIG. 1.

FIG. 2.

FIG. 4.

FIG. 5.

FIG. 3.FIG. 6.FIG. 7.

FIG. 1 is a side elevation of a copy paper carton embodying my new design, the side opposite thereto being similar in appearance;

FIG. 2 is a top plan of the carton of FIG. 1;

FIG. 3 is a bottom plan of the carton of FIG. 1;

FIGS. 4 and 5 are end elevations as seen from the left and right, respectively, of the carton in FIG. 1; and

FIGS. 6 and 7 are enlarged fragmentary sections taken along the lines 6-6 and 7-7 in FIG. 1.

I claim:

The ornamental design for a copy paper carton, substantially as shown and described.
